UNITED STATES PATENT OFFICE.

WALTER H. PETERS, OF ELMHURST, ILLINOIS.

FENDER.

No. 872,449.

Specification of Letters Patent.

Patented Dec. 3, 1907.

Application filed March 7, 1907. Serial No. 361,134.

To all whom it may concern:

Be it known that I, WALTER H. PETERS, a citizen of the United States, residing at Elmhurst, in the county of DuPage and State of Illinois, have invented certain new and useful Improvements in Fenders, of which the following is a description.

My device belongs to that class of devices known as fenders for use on automobiles, street cars or other vehicles, and particularly a folding or closing fender for the purposes stated, and has for its objects the production of a simple, cheap, durable and more efficient fender. This fender is particularly designed for use on automobiles and like vehicles, but it is obvious that it may be used on street cars or on any other form of vehicle on which the same may be desired.

To this end my invention consists in the novel construction, arrangement and combination of parts herein shown and described and more particularly pointed out in the claims.

In the drawings wherein like reference characters indicate like or corresponding parts, Figure 1 is a side elevation of my preferred form of fender as applied to an automobile, the same shown in its closed or folded position; Fig. 2 is a top view of the same, the open position of the wings shown in dotted lines; Fig. 3 is a front elevation of the same; Fig. 4 is a partial perspective view of one of the guard wings showing in detail a portion of the preferred means for operating the fender wings; Fig. 5 is a side elevation of the fender showing a slightly modified means for securing and supporting the fender on an automobile; Fig. 6 is a top view of the modified supporting means; Fig. 7 is a perspective detail view showing my preferred means for pivotally securing the wings to the frame; Fig. 8 is a partial view in elevation of the rear of the fender, and Fig. 9 is a partial cross-sectional view of the back frame and guard wings.

Referring to the drawings, my preferred form of fender consists of a main or substantially horizontally extended frame 1 and wings pivotally secured thereto, adapted to open or close as shown. The frame is made triangular or V-shaped, the point of the V being the front of the frame, and provided with a back or substantially vertically extended frame 6. The wings are made up of

a plurality of bars or rods 2, each rod being provided with a ball 7 at one end adapted to fit into, or pivot in a coöperating socket or pocket in the frame 1. On the outer or free ends of the bars 2 are secured the bars or members 3, the same being preferably pivotally secured thereon by means of the balls 8 on the rods 2 and coöperating pockets in the bars 3 as shown. The pockets in the main frame may be constructed in any suitable or preferred way. As shown, the frame 1 is provided with a removable portion 1', a portion of the socket lying in both parts 1 and 1'. A suitable ledge or extension 35, or its equivalent, may be provided on the frame 1 (see Fig. 7), adapted to support the bars 2 or 70 the fender wings when open, if the same is desired. It is obvious that any other suitable or preferred means for pivotally securing the wings to the frame, or the bars 3 on the rods 2 may be employed to accomplish 75 the results desired. It is likewise obvious that there may be any number of bars 2 and their general form or design may be varied to suit individual preferences. It is not necessary that there be the same number of bars 2 in each wing.

When the wings are closed or folded the bars or members 3 at the free ends of the wing members, lie substantially transversely to the longitudinal axis of the frame 1; that is, they lie in substantially the same plane as the back or vertically extended frame 6. When the fender is open or the wings extended (see dotted lines in Fig. 2) the wings lie in substantially the same plane as the main frame 1. Any suitable or preferred means may be employed to operate the wings, my preferred means for the purpose being more fully explained hereinafter.

In the preferred construction, to more fully guard the wheels 33 I provide what may be termed guard wings 12. To distinguish the two sets of wings I shall herein designate wings 2 as fender wings and wings 12 as guard wings. The guard wings 12 are adapted to slide out and cover or guard the wheels 33 when the fender wings 2 are extended or open, as shown in dotted lines Fig. 2. The guard wings are also shown extended in Fig. 3 (see dotted lines). In my preferred construction, the frame 6 is provided with extensions 6' so that the guard wings 12 are retained in position by the

frame 6 and its extensions 6' as is shown in Figs. 8 and 9. Any suitable means may be employed to operate these wings, the preferred way being to arrange the operating means so that the fender wings 2 and guard wings 12 will be operated simultaneously. To accomplish this end I provide means to positively operate the guard wings, and connecting means between the fender and guard wings to operatively transmit the movement of the guard wings 12 to the fender wings 2 to open or close the same. By shifting the lever 23 the operating bar 22 is pushed forward or back and its movement transmitted to the other members 24—24 which are pivotally secured to the wings 12 at 25 to slide the guard wings in and out as desired. The brackets 25 on the guard wings 12, to which the rods 24 are secured, are preferably made adjustable on the wings so that the travel of the guard wings may be adjusted to any particular machine or desired travel.

The movement of the guard wings 12 is transmitted to the fender wings 2 to operate the same through the racks 13, which are secured to the wings 12 and through the pinions 11, 11, couplings 10, 10, shafts 9, 9, and arms 4, 4. One end of each of the arms 30 4 is secured on the shafts 9, and the other ends fit into pockets or sockets 5, 5 in the bars or members 3, 3, so that as the arms 4 are lowered or raised by means of the operating members stated, the fender wings 2 are 35 folded or opened as heretofore described. To permit the shaft 9 to lie along the lower edge of the frame 1 a universal coupling 10, or its equivalent, is preferably used. The rack 13 is preferably adjustably secured on 40 the wings 12 so that it may be adjusted to suit any particular machine or vehicle or for any desired travel of the fender wings.

Any suitable means may be employed to secure and support the fender on the vehicle. As shown, the preferred way is to so arrange the fender that its height from the ground or that is its vertical position relative to the vehicle may be controlled as desired. For this purpose I preferably provide supporting bars 17—17' on each side of the frame 15 of the vehicle. The supporting bars are resiliently supported by springs 19, or the equivalent for the purpose, on the axle 16 as shown. The ends 17 of the bars 55 17—17' are connected to the fender frame and the other ends 17' extended to a convenient place for operating same. These supporting bars, one on each side, are operated by suitable levers 18, or the like. It 60 is obvious that the supporting bars may be so arranged as to be operated by levers on each side of the vehicle or to be operated simultaneously by one lever. When this form of supporting bar 17—17' is used, I 65 guide the upper part of the fender in its ver-

tical travel by means of a grooved guide member 20 secured to the frame 15 or other suitable part of the vehicle, adapted to co-operate with member 21 secured to the vertical frame 6 of the fender.

When the fender is in use on a vehicle, the wings, both fender and guard, are preferably operated by means of a hand-lever 23, suitable means being arranged to transmit the movement of the lever to the wings. In the 75 form shown in the drawings, the movement of the lever 23 is transmitted through the connecting rod or bar 22, and connecting bars 24—24, to the guide-wings 12—12 which are pushed in or out depending upon 80 which direction the lever 23 is shifted. The guide-wings operate the shaft members 9—9 through the racks 13—13, and gears 11—11, the gears being connected to the shaft members 9 by the universal couplings 10—10. 85 As heretofore stated each of the shaft members 9 has secured thereto an arm 4, or is otherwise suitably connected to one of the rods 2, so that as the shaft is turned the fender wings are operated or closed as desired. 90 In this construction shown the guard and fender wings are therefore simultaneously operated, by the shifting of lever 23. The fender is raised or lowered by raising or lowering the end 17' of the bars 17—17', the operation being brought about by operating the foot lever 18.

Figs. 5 and 6 show a slightly modified arrangement of the guiding member. In this form the bar 26—27 is pivotally secured to 100 the vehicle and the spring 28 provided so that the member 21 operating or sliding in the grooved member 20 is partially resiliently supported by the spring 29 and that by the bar 26—27 and spring 28, the spring 28 105 being somewhat stiffer than the spring 29. The back frame 6, main frame 1, and the guide wings 12 may be provided with a suitable wire netting 32—34 and 31 respectively, if it is so desired.

Having thus described my invention, it is obvious that various immaterial modifications may be made in the arrangement, construction, form and operating mechanism of my preferred form of device, as shown in the drawings without departing from the spirit of my invention, hence I do not wish to be understood as limiting myself to the exact form or arrangement shown.

What I claim as new, and desire to secure 120 by Letters Patent is:—

1. A fender of the kind described, comprising a main frame and wings pivotally secured thereto, said wings arranged to lie in substantially the same plane as the main 125 frame when open, but lie with their free edges transversely of the frame when closed.

2. A fender of the kind described, comprising a main frame and wings pivotally secured thereto, said wings arranged to lie 130

- when open in substantially the same plane as the main frame, but to lie with the free edges transversely of the frame when closed, and means for operating said wings.
5. 3. A fender of the kind described, comprising a horizontally extended frame, and a substantially vertically extended frame, in combination with fender wings pivotally secured to the horizontal frame and arranged 10 to lie in substantially the plane of the horizontal frame or to lie with the free edges in the plane of the vertical frame as desired.
4. A fender of the kind described, comprising a substantially horizontally extended frame and a substantially vertically extended frame, in combination with fender wings pivotally secured to said horizontal frame and arranged to lie in substantially the plane of the horizontal frame or with the free edges 20 in the plane of the vertical frame as desired, and means for pivotally securing said wings to the frame.
5. A fender of the kind described, comprising a horizontally extended frame and a substantially vertically extended frame, in combination with fender wings pivotally secured to said horizontal frame and arranged to lie in substantially the plane of the horizontal frame or with free edges in the plane 30 of the vertical frame as desired, and coöperating guard wings.
6. A fender of the kind described, comprising a horizontally extended frame and a substantially vertically extended frame, in combination with fender wings pivotally secured to the horizontal frame and arranged to lie in substantially the plane of the horizontal frame or with the free edges in the plane of the vertical frame as desired, coöperating guard wings, and means for operating said fender and guard wings.
7. In a device of the kind described, a frame and means for adjustably securing the same to a vehicle, in combination with folding fender wings pivotally secured to the frame, and means for operating said wings.
8. In a device of the kind described, a frame and means for adjustably securing the same to a vehicle, and means for controlling the vertical position of the frame relative to the vehicle, in combination with folding fender wings pivotally secured to the frame, and means for operating said wings.
9. In a device of the kind described, a substantially horizontally extended frame and adjustable means adapted to support the frame and control its vertical position relative to a vehicle, in combination with folding fender wings pivotally secured to the frame, 50 means for pivotally securing said wings comprising ball and socket joints, and means for operating the wings.
10. In a device of the kind described, a frame in combination with a pair of wings 60 pivotally secured to the frame on the sides thereof, means for operating said wings, co-operating guard wings, and means for operating said guard wings.
11. In a device of the kind described, a frame and means for supporting the frame on a vehicle and controlling its vertical position relative to the vehicle, in combination with a plurality of fender wings pivotally secured to the frame on the sides thereof, co-operating guard wings, said guard wings arranged to control the position of said fender wings, and means for operating said guard wings.
12. In a device of the kind described, a frame in combination with fender wings pivotally secured to the frame on the sides thereof, coöperating guard wings, and means for simultaneously controlling said fender and guard wings.
13. In a device of the kind described, a frame, means for supporting the frame on a vehicle and controlling its vertical position relative to the vehicle, in combination with a plurality of fender wings pivotally secured to the frame on the sides thereof, coöperating guard wings, and means for simultaneously operating said fender and guard wings.
14. In a device of the kind described, a substantially horizontally extended V-shaped frame and means for securing and supporting said frame on a vehicle with the point of the V in front, in combination with fender wings pivotally secured on the sides of said frame, and means for operating said wings as desired.
15. In a device of the kind described, a substantially horizontally extended V-shaped frame, means adapted to adjustably secure and support the frame on a vehicle, and means for controlling the vertical position of the frame relative to the vehicle, in combination with fender wings secured on the sides of said frame, and means for operating said wings as desired.
16. In a device of the kind described, a substantially horizontally extended V-shaped frame, and means for securing and supporting said frame on a vehicle, in combination with fender wings pivotally secured to said frame on the sides thereof, coöperating guard wings, and means for operating said fender and guard wings.
17. In a device of the kind described, a substantially horizontally extended V-shaped frame, and means adapted to adjustably secure and support the frame on a vehicle and means for controlling the vertical position of the frame relative to the vehicle, in combination with fender wings pivotally secured to said frame, coöperating guard wings, and means for operating said fender and guard wings.
18. In a device of the kind described, a substantially horizontally extended V-shaped frame, means adapted to adjustably secure

and support said frame on a vehicle and means for controlling the vertical position of the frame relative to the vehicle, in combination with fender wings pivotally secured 5 to said frame, coöperating guard wings, and means for operatively transmitting the movement of said guard wings to the fender wings, and means for operating said guard wings.

19. In a device of the kind described, a substantially horizontally extended V-shaped frame and a vertically extended back frame, means for adjustably securing the said frames on a vehicle, in combination with coöperating fender wings pivotally secured to the 10 V-shaped frame, the free edges of said wings arranged to lie in substantially the same plane as the horizontal frame or against the vertical frame as desired, and means for operating said wings.

20. In a device of the kind described, a substantially horizontally extended frame and a vertically extended back frame, means for securing said frames on a vehicle, in combination with coöperating fender wings pivotally secured to the horizontal frame, the 15 free edges of said wings arranged to lie in substantially the same plane as the horizontal frame, or to lie against the vertical frame as desired, slideable coöperating guard wings 25 guided by said vertical frame, and means for operating the fender and guard wings.

21. In a device of the kind described, a substantially horizontally extended frame and a vertically extended back frame, means for securing said frame on a vehicle, in combination with coöperating fender wings pivotally secured to the horizontal frame, the 30 free edges of said wings arranged to lie in substantially the same plane as the horizontal frame, or to lie against the vertical frame as desired, slideable coöperating guard wings 35 guided by said vertical frame, and means for simultaneously operating the fender and guard wings.

40 22. In a device of the kind described, a substantially horizontally extended frame and a vertically extended back frame, means for securing said frames on a vehicle, in com- 45

bination with coöperating fender wings pivotally secured to the horizontal frame, means 50 for pivotally securing the wings to the frame, comprising coöperating ball and socket members, the free edges of said wings arranged to lie in substantially the same plane as the horizontal frame, or to lie against the vertical frame as desired, slideable coöperating guard wings 55 guided by said vertical frame, means for operating the guard wings, and means for operatively transmitting the movement of the guard wings to the fender wings.

23. In a device of the kind described, a substantially horizontally extended frame and a vertically extended back frame, means for securing said frames on a vehicle, in combination with coöperating fender wings pivotally secured to the horizontal frame, the 60 free edges of said wings arranged to lie in substantially the same plane as the horizontal frame, or to lie against the vertical frame as desired, slideable coöperating guard wings 65 guided by said vertical frame, means for operating the guard wings, means for operatively transmitting the movement of the guard wings to the fender wings, said means comprising racks, pinions and coöperating 70 shafts, and means for operatively transmitting the movements of the shafts to the fender wings.

24. A fender of the kind described, comprising a main frame, and a back frame, 80 means for resiliently supporting said frames on a vehicle, means for controlling their vertical position relative to the vehicle, in combination with coöperating fender wings pivotally secured to said main frame, and movable coöperating guard wings, and means for simultaneously operating said fender and 85 guard wings.

In testimony whereof, I have hereunto signed my name in the presence of two sub- 90 scribing witnesses.

WALTER H. PETERS.
